(57) **CLAIM**

The ornamental design for a lighting fixture mountable on an overhead support, as shown and described.

DESCRIPTION

In a preferred embodiment, the nature of this product is as a light mountable from a ceiling.

FIG. 1 is a bottom, frontal perspective view of a lighting fixture mountable on an overhead support embodying my new design;

FIG. 2 is a bottom plan view thereof;

FIG. 3 is a front elevational view thereof, the rear elevational, right side elevational, and left side elevational views thereof being identical to the front elevational view shown; FIG. 4 is a top plan view thereof;

FIG. 5 is a bottom, frontal view of a second embodiment;

FIG. 6 is a bottom plan view thereof;

FIG. 7 is a front elevational view thereof, the rear elevational, right side elevational, and left side elevational views thereof being identical to the front elevational view shown; FIG. 8 is a top plan view thereof, and of the FIG. 9 embodiment;

FIG. 9 is a bottom, frontal perspective view of a third embodiment;

FIG. 10 is a bottom plan view thereof; and,

FIG. 11 is a front elevational view thereof, the rear elevational, right side elevational, and left side elevational views thereof being identical to the front elevational view shown. The broken line representations of mounting hanger structures in FIGS. 1, 3, 5, 7, 9 and 11, ceilings in FIGS. 3, 7 and 11, and venting holes in FIGS. 4 and 8 are for the purpose of illustration only, and form no part of the claimed design.
